UNITED STATES PATENT OFFICE

160,392

BRASSIÈRE

Hyman G. Imôn, Buffalo, N. Y., assignor to Jaye
Imôn Inc., a corporation of New York

Application December 31, 1949, Serial No. 6,962

Term of patent 14 years

(Cl. D20—4)

To all whom it may concern:

Be it known that I, Hyman G. Imôn, a citizen of the United States, residing at Buffalo, in the county of Erie and State of New York, have invented a new, original, and ornamental Design for Brassière, of which the following is a specification, reference being had to the accompanying drawing, forming a part hereof.

Fig. 1 is a front elevational view of a brassière showing my new design.

Fig. 2 is a perspective view thereof as it appears without the rear ends being fastened together.

Fig. 3 is a rear perspective view thereof, conventional fastening means being shown in dotted lines for fastening the rear ends of the brassière together.

Fig. 4 is a side elevational view thereof.

The essential feature of my design resides in the portion shown in full lines on the drawing.

I claim:

The ornamental design for a brassière, as shown and described.

HYMAN G. IMÔN.
